STUART PARMELEE MILLER, OF GLEN RIDGE, NEW JERSEY, ASSIGNOR TO THE BARRETT COMPANY, OF NEW YORK, N. Y., A CORPORATION OF NEW JERSEY

RECOVERY OF CREOSOTE OILS, TAR ACIDS, ETC.

Application filed July 16, 1927. Serial No. 206,367.

This invention relates to the recovery of commercially useful products directly from hot coal distillation gases, and particularly from coke oven gases. The products recovered include creosote oil and carbolic oil, as well as pitch of high melting point and low carbon content, ammonia, etc.

The common method of producing creosote and carbolic oils is by distillation of coal tar in ordinary tar stills. The lighter oils first distilled are the carbolic oils, while the higher boiling point distillate forms the creosote oils. The residue of the distillation is a pitch relatively high in carbon content, the distillation being accompanied by a very considerable decomposition of oil constituents of the tar, with resulting decrease in yield of oils distilled and increase in pitch residue and in carbon content of the pitch residue. The creosote and carbolic oils contain only such undecomposed constituents of the tar as distill without decomposition, together with such condensable decomposition products as are of a volatile character at the temperatures of the distillation. When the distillation is carried to high temperature for the obtaining of a large yield of creosote oil, the decomposition is particularly marked, and the relative increase in pitch residue and carbon content thereof is correspondingly greater.

Such distillation of tar for the production of creosote oil and carbolic oil is commonly carried out at tar distillation plants at a greater or less distance away from the coke oven plants where the tar is produced, requiring transportation of the tar from the coke oven plant to the tar distillation plant with attendant expenses and handling losses.

The present invention provides an improved process whereby the production of tar at the coke oven plant and its handling and shipment and subsequent distillation at a tar distillation plant are obviated, and whereby the expense and losses incident to handling and transportation are eliminated or minimized.

According to the present invention, creosote oil and carbolic oil are directly produced at the coke oven plant from the coke oven gases, in a marketable form, requiring no further

treatment, and there is simultaneously produced a pitch residue of low carbon content.

According to the present invention, the hot coal distillation gases from the ovens or retorts are subjected to a limited and regulated cooling to a lower but still high temperature, such that there is separated out and carried in suspension in the hot gases particles of pitch of high melting point, while leaving the greater part of the oils of the gases in vapor form. The gases so cooled to a regulated temperature are then subjected to a cleaning operation for the removal of the pitch particles therefrom, leaving clean gases containing vapors of oil suitable for creosote oils and carbolic oils. The cleaned gases are then subjected to further cooling in successive stages, first to a temperature around, e. g., 85 to 100° C., and then to a low temperature, around 25 to 35° C., and there is directly condensed and recovered therefrom a higher boiling creosote oil and a carbolic oil, which oils contain constituents which do not readily boil and distill without decomposition, and which oils are in this and other respects distinguished from ordinary creosote and carbolic oils. After the separation of the creosote and carbolic oils from the gases, they are subsequently passed through an ammonia absorber or saturator, and then through a light oil scrubber or absorber for the recovery of light oils such as benzol.

In my prior application, Serial No. 202,736, I have set forth a process whereby tar acid oils are directly recovered from hot coal distillation gases by subjecting the gases to a cleaning treatment to remove pitch particles therefrom at a sufficiently high temperature to leave carbolic or tar acid oils in vapor state, then cooling the cleaned gases to separate a tar acid oil therefrom and extracting the tar acids from such oils.

In my companion application Serial No. 206,366 I have set forth a process in which a creosote oil is directly recovered from hot coal distillation gases by cleaning the gases at a high temperature to separate pitch particles therefrom, then cooling the cleaned gases to a low temperature, around 25° to 100

35° C., to separate therefrom a creosote oil containing both high boiling and low boiling constituents, blended together to form a balanced oil composition suitable for use directly for creosoting purposes.

The improved process of the present invention provides for the recovery from the hot coal distillation gases of both a creosote oil and a carbolic or tar acid oil by cleaning 10 the hot gases at a sufficiently high temperature to leave therein oils including heavy oils, and then subjecting the hot cleaned gases to cooling first to a temperature such that a creosote oil will be separated therefrom and subsequently to further cooling to a temperature such that carbolic or tar acid oil will be separated therefrom.

The creosote oils produced in accordance with the present invention may, to a large 20 extent, be similar to the creosote oils produced in accordance with my companion application Serial No. 206,366, but will be substantially free from the lighter oil components, which are separately recovered as 25 carbolic oils.

The cooling of the hot coke oven gases, according to the present invention, is regulated and limited so that only the heavier constituents which form a relatively high 30 melting point pitch are separated therefrom, i. e., converted from a vapor to a liquid condition. As the temperature of the hot gases is lowered from the maximum of 600° to 700° C. or higher, at which the gases escape from 35 the ovens, the heavier pitch constituents which are originally present in the form of vapors, are progressively condensed as the temperature is lowered, and they, together with any suspended particles of carbon, etc., 40 will be removed from the gases by the cleaning operation. The initial cooling of the gases can be effected by a limited spray or contact with water or ammonia liquor, or by regulated atmospheric cooling while the 45 gases are passing through pipes or conduits exposed to the atmosphere. The gases can be collected in the ordinary collector mains and subjected therein to a regulated cooling, as by the limited introduction of ammonia 50 liquor into contact therewith. Such cooling by ammonia liquor may result in local overcooling of some of the gas and separation of heavy tar therefrom in the collector main, but the average temperature of the gases 55 leaving the collector main can be maintained sufficiently high so that a relatively high melting point pitch can be separated therefrom when the gases are subjected to the cleaning treatment.

60 The cleaning of the gases at a regulated temperature can be effected by a sufficiently intimate scrubbing with hot pitch; for example, hot pitch having a temperature and composition the same as or similar to that of 65 the pitch particles carried in suspension in

the gases. The cleaning is more advantageously effected, however, by an electrical precipitator through which the gases are passed and in which they are subjected to the action of high tension electric current. The cleaning treatment is carried out without any considerable further reduction in temperature, so as to leave in the gases escaping from the precipitator the desired heavy oils. 70

The cooling of the cleaned gases from the high temperature of the cleaning operation to the lower temperature of around 25° to 35° C. is carried out in successive stages so that there is thus separated therefrom an oil suitable for use directly as a creosote oil, and so that there is subsequently separated from the gases a lighter oil rich in phenols or tar acids, which oil forms a valuable carbolic oil. After the gases have been so cooled and the respective oils removed therefrom, they are then passed through an ammonia absorber or saturator, for the recovery of ammonia, and then to a scrubber or absorber for the recovery of light oils such as benzol. 80

The temperature to which the gases are cooled before they are subjected to the cleaning treatment, is a relatively high temperature, so that a large yield of oil vapors is retained therein, and so that a relatively high melting point pitch is obtained. The melting point of the pitch will increase or decrease as the temperature at which the gases are cleaned is raised or lowered, and the proper temperature of operation can be readily determined and regulated by the character of the pitch produced, particularly as different coal distillation gases may require different temperatures for the preparation of pitch of the same melting point. 90

With the direct production of a lower melting point pitch, for example, having a melting point around 145° F., the yield of creosote oil will be materially less than when a higher melting point pitch is directly recovered and an increased amount of heavy oils left as vapors in the cleaned gases. Even with the production of a melting point of a pitch at around 145° F., however, there can be produced a creosote oil suitable for use directly for commercial purposes. Such an oil can be obtained, for example, in a yield representing around 10 to 20 percent of the tar which would ordinarily be recovered from the gases. In addition, there can be recovered from the gases a carbolic oil representing around 15 to 20 percent of the tar which would ordinarily be recovered from the gases. The creosote oil obtained when such a relatively low melting point pitch is produced will be relatively free from the heavier oil constituents, but it will also be free, or relatively free, from the lighter carbolic oil constituents, so that it will be an intermediate oil having properties which adapt 110

120

125

130

it for use without further treatment, as a creosote oil.

When the cleaning of the gases is carried out at a higher temperature to produce a higher melting point pitch residue, for example, a pitch of melting point around 160° to 170° F., an increased yield of creosote oil can be directly recovered from the gases, while a similar yield of carbolic oil can be 10 subsequently recovered at a lower temperature. If the cleaning is carried out at a still higher temperature, to leave a pitch of, for example, 200° F. or 300° F., or even 400° F. melting point, the creosote oil recovered from 15 the gases will be a heavier creosote oil, rich in high boiling and heavy constituents, including constituents which are normally of a grease or resin-like character, but which in admixture with the other oil constituents 20 blend therewith to form a homogeneous liquid. These grease or resin-like constituents form valuable components of the creosote oil, since they remain as a residue in the creosoted material after the volatile oils have 25 been to a large extent volatilized or vaporized.

The creosote oil composition produced in accordance with the present invention will have a relatively high initial boiling point. Instead of having a boiling point such that a 30 small percentage will be distilled at temperature up to 210° C., in general an appreciably higher temperature will be required before any considerable amount of the oil will be vaporized, although it is not essential that the 35 oil should be free from constituents such that when heated to temperatures of 210° C. some distillation will take place. As compared with the creosote oils produced in accordance with my companion application 40 (Serial No. 206,366), the creosote oil produced in accordance with the present process will, when it contains heavy constituents and is produced from gases from which pitch of the same melting point has been separated, 45 be a heavier creosote oil, being free from the light carbolic oil constituents which are retained in the creosote oil composition produced according to the process of my said companion application. When the creosote 50 oil produced according to the process of the present invention, is an intermediate oil, produced from gases from which a lower melting point pitch has been separated, it will likewise be a somewhat heavier creosote oil in the sense that it will be free from or contain 55 less of the lower boiling oil constituents which are separately recovered, according to the present invention, as a separate carbolic oil product.

60 The temperature to which the gases are cooled in the creosote oil condenser will vary somewhat with the composition and origin of the coal distillation gases, but in general the temperature will, for ordinary coke oven 65 gases, be around 80° to 100° C., or in some

cases around 85° to 90° C., such that the oils desired in the carbolic oil product will be retained in vapor state in the gases leaving the creosote oil condenser, although it is not essential that a sharp fractionation or separation be obtained. 70

The gases leaving the creosote oil condenser then pass to the carbolic oil condenser, where they are cooled to a low temperature, around 25° to 35° C., to separate the carbolic oil therefrom. The gases then pass to the ammonia absorber or saturator for the recovery of ammonia, and then to the light oil absorption system. 75

The condensers for separating the creosote oil and carbolic oil directly from the gases may be of either the indirect type, cooled by indirect contact with the cooling medium, or direct condensers in which the cooling liquid is directly introduced into the 80 hot gases. If cooling liquid is introduced directly into the gases in the creosote oil condensers, the temperature of the liquid should be regulated so that local over-cooling is not obtained, and a large amount of the carbolic 85 oil thrown down with the creosote oil, although some of the carbolic oil can be so thrown down and included in the creosote oil. The cooling of the gases in the creosote oil condenser can advantageously be obtained by 90 the introduction into the gases of some of the carbolic oil supplemented by external cooling, since the vaporization of the carbolic oil will tend to give a closer separation between the 95 creosote and carbolic oil products. 100

The cooling of the gases in the carbolic oil condenser can advantageously be carried out with direct introduction of water or ammonia liquor, in which case the ammonia liquor is advantageously free from tar, so that a clean 105 or tar-free ammonia liquor is directly obtained, from which the ammonia can be recovered without contaminating tar impurities. Even with indirect cooling of the gases in the carbolic oil condenser, there will be 110 condensed more or less water with the oils in the form of dilute ammonia liquor, which will, however, be clean ammonia liquor, free from tar.

The gases leaving the carbolic oil condenser are then passed through the ammonia absorber or saturator, where the ammonia is combined with sulphuric acid to form ammonium sulphate, or is absorbed in water to produce ammonia liquor. The gases may be 115 passed to the acid saturator without reheating, or they may be reheated to a higher temperature before they pass to the saturator. After the gases escape from the saturator or absorber, they then pass to a scrubber or absorber where the light oils are recovered therefrom, for example, by scrubbing them in an absorbent oil, such as "straw" oil. 120

The present process presents the advantage that the oils recovered are clean oils, 125 130

i.e., substantially free from heavy tar or pitch constituents, while the gases, being likewise free from such constituents, can advantageously be treated in the ammonia saturator 5 and in the benzol absorber for the recovery of benzol and ammonia free from tar contamination. The advantages of freedom from heavy tar or pitch constituents are thus obtained throughout the subsequent treatment of the 10 gas, while the heavy tar or pitch constituents are directly recovered in the form of a pitch of regulated melting point suitable for use directly as a commercial product or to be employed by blending or compounding it with 15 tar or other pitch constituents for commercial purposes. The pitch will be materially different from ordinary pitch produced as a residue from the distillation of tar in ordinary externally heated tar stills. As compared 20 with pitch of the same melting points, it will have a radically lower carbon content, and be obtained in considerably decreased yield, while the oil recovered will be considerably 25 increased in amount as compared with the amount of oil recovered from tar by ordinary distillation.

In particular, the decomposition of oil constituents which takes place in ordinary tar stills is eliminated, or substantially so, in 30 the process of the present invention, so that there is present in the directly recovered creosote and carbolic oils, constituents which are not present in ordinary creosote and carbolic oils, but which are decomposed 35 or destroyed or converted into other products during the ordinary tar distillation process.

Therefore the creosote and carbolic oils can, however, be employed to advantage in 40 place of ordinary carbolic and creosote oils. The creosote oils can be used, for example, directly for creosoting purposes, or they can be blended or admixed with tar or other creosote oil components to form composite products, such as solutions of coal tar in the 45 improved creosote oils or blends of directly recovered tarry oils with the new creosote oils to give composite creosoting compositions of the character described in my companion application, Serial No. 199,629.

The carbolic or tar acid oils produced by the present process can be marketed as carbolic oils or they can advantageously be extracted for the recovery of tar acids of phenols therefrom, for example, in accordance with the process described in my companion application, Serial No. 202,736.

The invention will be further described 60 in connection with the accompanying drawings, which illustrate in a somewhat conventional and diagrammatic manner an arrangement of apparatus adapted for the practice of the process of the invention.

65 In the accompanying drawings,

Fig. 1 is a plan showing the arrangement of the apparatus;

Fig. 2 is an elevation; and

Fig. 3 is an elevation with parts in section showing one form of electrical precipitator for cleaning the hot gases. 70

In the apparatus illustrated, a coke oven block is shown conventionally at 1, having the usual uptake pipes 2, leading to a collector main 3, common to a number of ovens. 75 The gases from the collector main pass through the main or pipe 4, to an electrical precipitator 5, in which the gases are treated at a high temperature to separate pitch therefrom. The gases then pass through the cross-over main 6, to the first condenser 7 for the creosote oil, shown as an indirect type of cooler with indirect cooling with water, and with means for spraying lighter oil, such as carbolic oil, directly into the 80 gases in the top of the cooler, through line and nozzles 50. From the condenser 7 the gases then pass through the pipe 8 to the condenser 9 for carbolic oil, and then through the line 10 to the exhauster 11, and 85 then to the ammonia absorber or saturator 12, shown as a sulphuric acid saturator, the light oil scrubber 13, and then out through the pipe 14, to a place of storage indicated 90 at 51.

Spray pipes 15 are provided for spraying a regulated amount of ammonia liquor into the gases entering and in the collector main, but the amount of liquor so sprayed is limited, so that the gases escape from the collector main at the desired high temperature, for example, at temperatures up to around 250° C., for example, where a pitch of melting point around 300° F. is to be separated from the gases, although the temperature of cleaning of the gases will vary somewhat with different gases to give a pitch of any particular melting point. 105

The cooling of the gases in the collector main, particularly with local over-cooling of some of the gas in contact with the ammonia liquor, may result in throwing down a heavy tar in the collector main, which can be drawn off, together with any unvaporized ammonia liquor through the center box 16 110 and pipe 17 to receptacle 18. Considerable ammonia liquor can be circulated through the bottom of the collector main, to carry away with it any deposited tar without cooling the gases to too low a temperature, if the ammonia liquor sprays are omitted or limited, since a part only of the gas will be cooled by the ammonia liquor, while a large part of the gas will escape cooling, so that the resulting mixture of gases leaving the 115 collector main will be at the desired high temperature.

The pitch particles carried in suspension in the gases entering the electrical precipitator 5 will be thrown down therein and col- 120 125 130

lected in the bottom thereof, and can be drawn off through the line 19, to the pitch receptacle 20. The gases leaving the electrical precipitator and entering the cross-over main 6 will still be at a high temperature, carrying a large amount of oils in vapor form. These gases will be cooled in passing through the cross-over main 6, and will be further cooled in the first condenser 7, which will be regulated in temperature so that the creosote oil will be directly condensed therein and run out through the line 21, to the creosote oil receptacle 22. Oil condensed in the cross-over main may likewise be drawn off through the line 27 to this same receptacle. The gases will be cooled in the condenser 7, to a regulated temperature e. g., around 85 to 90° C., or in general, to a temperature between 80° and 100° C., so as to leave in vapor form the oils desired in the carbolic oil products. The gases then pass into the condenser 9, where they are cooled to a low temperature, around 25° to 35° C., and the carbolic oil separated therefrom. This cooling can advantageously be effected by sprays 28 of water or tar-free ammonia liquor, and the resulting oil and ammonia liquor can be drawn off to the decanter or receptacle 24, and the ammonia liquor and oil separated from each other and separately collected in the receptacles 25 and 26. The ammonia liquor can be used over again for cooling the gases or fresh oil or cooler ammonia liquor can be employed. The ammonia liquor will be clean liquor in the sense that it will be free from tar and can therefore be more advantageously handled for the recovery of ammonia therefrom.

The gases leaving the condenser 9 at a temperature around 25° to 35° C., will pass through the exhauster 7 and then, for example, to the saturator 12, where the ammonia will be combined with sulphuric acid to form ammonium sulphate and the gases will then pass through the light oil scrubbing system 13, where the gases will be scrubbed with a suitable oil, such as creosote oil or "straw oil" to absorb the benzol, etc. from the gases, after which the benzol can be recovered from the absorbent by distillation.

The electrical precipitator illustrated in Fig. 3 comprises a shell of, for example, cylindrical form, having a gas inlet 30 near the lower end thereof and a gas outlet 31 near the upper end, these inlets and outlets being for the introduction of the hot coke oven gases and the exit of the hot cleaned gases. A baffle 32 partially separates the lower chamber 33 from the electrode chamber 34. A plurality of tubes 35 is supported in headers 36, and form the positive electrode of the separator, the shell of which is grounded. Bus bar 37 supports the electrodes 38 in spaced relation to the walls of the tubes 35. The bus bar 37 extends through openings 39 into cham-

bers 40, in which insulators 41 support the bus bar, which is connected to any suitable source of high tension current. Coils 42 may be disposed in the chambers 40, around the insulators 41, for heating this chamber 70 when desired, and heating medium may also be passed through the jacket surrounding the tubes by means of inlet and outlet 43 and 44, or the tubes of the electrical precipitator, and the precipitator itself, may be surrounded with insulating material (not shown) so as to prevent or reduce loss of heat by radiation while the gases are passing through the precipitator. 75

In the operation of this electrical precipitator, the gas enters through the inlet 30, passing around the baffle 32, and thence upwardly through the tubes 35, where the high tension discharge between the electrodes 38 and tubes 35 effect removal of substantially all solid and suspended pitch particles from the gases in the form of a directly recovered high melting point pitch, which flows down over the baffle 32 into the chamber 33, and thence to the outlet pipe 19. 80

The pitch directly recovered by the process can be employed directly as a merchantable product and used for briquetting or fuel or other purposes, or it can be blended with other pitch or tar constituents to form a composite product, for example, a composite product such as described in my companion application, Serial No. 199,451, in which the hot high melting point pitch is blended with raw tar, etc., to form a new pitch composition. 90 Where a pitch of desired high melting point is to be produced, the operation can be regulated as described in my said companion application, Serial No. 199,451, and the pitch can then be employed as described in said application. 100 The process of the present invention is not, however, limited to the use of pitch for the production of such new pitch compensations, but the pitch can be directly employed, for example, for briquetting purposes, or for fuel purposes, or for other purposes for a high melting point pitch of low carbon content if desired. 105

It will thus be seen that the present invention eliminates the production of pitch at the coke oven plant and its shipment to a tar distillation plant, and its distillation at such plant for the production therefrom of distillate oils and pitch residues; the present invention providing an improved and simplified process, whereby not only a high melting point pitch but a pitch of low carbon content can be directly produced without distillation, and whereby an increased yield of an improved creosote oil can be directly recovered without requiring distillation, and whereby a carbolic or tar acid oil can also be directly recovered without having recourse to distillation, and whereby the ammonia recovery is 115 120 125 130

also improved by providing a gas free from tar. The present invention has the further advantage, among others, that it can be carried out in existing equipment of a by-product coke oven system, with only such changes as are required, for example, for the installation of an electrical precipitator with its connecting piping and means for regulating the temperature of the gases before they reach the electrical precipitator and while passing therethrough, and with provision for separately condensing and collecting the creosote and carbolic oils.

References to pitch melting points are to be understood to refer to melting points determined according to the method described in "Methods of analysis used in the coal tar industry" by J. M. Weiss, The Journal of Industrial and Engineering Chemistry, Vol. 10, No. 10, October, 1918, page 817. The boiling points of creosote oils are to be determined by Method D-246-30 of the American Society for Testing Materials.

I claim:

1. The method of treating coal distillation gases whereby creosote oil and carbolic oil are produced directly from the gases, which comprises subjecting coal distillation gases to cleaning at a sufficiently high temperature to separate therefrom a pitch of relatively high melting point and to effect substantially complete elimination of suspended pitch particles therefrom while leaving a large amount of heavy oils in the form of vapors, the cleaning operation being effected without substantial cooling of the gases, subsequently cooling the cleaned gases to a temperature around 80-100° C. to separate therefrom a creosote oil and subsequently cooling the gases to a lower temperature around 25-35° C. to separate therefrom a carbolic oil before passing the gases thru an ammonia absorber.

2. The method of treating hot coke oven gases whereby creosote oil and carbolic oil are produced directly from the gases, which comprises cooling hot coke oven gases to a regulated temperature such that it retains a large amount of oil constituents in vapor form, treating the gases with an electrical precipitator to separate pitch particles therefrom and to give clean gases containing such oils as vapors and subsequently cooling the gases in stages to a temperature around 25-35° C. to separate therefrom first a creosote oil and then a carbolic oil before passing the gases thru an ammonia absorber.

3. The method of treating hot coke oven gases whereby creosote oil and carbolic oil are produced directly from the gases, which comprises cooling hot coke oven gases to a regulated temperature and subjecting such gases to a cleaning operation to effect substantially complete separation of pitch constituents therefrom in the form of a pitch

having a melting point in excess of 145° F., and subsequently subjecting the cleaned gases to successive condensing treatments at successively lower temperatures to separate therefrom first a creosote oil and then a carbolic oil before passing the gases thru an ammonia absorber.

4. The method of treating hot coke oven gases whereby creosote oil and carbolic oil are produced directly from the gases, which comprises cooling hot coke oven gases to a regulated temperature and subjecting such gases to a cleaning operation to effect substantially complete separation of pitch constituents therefrom in the form of a pitch having a melting point in excess of 200° F., and subsequently subjecting the cleaned gases to successive condensing treatments at successively lower temperatures to separate therefrom first a creosote oil and then a carbolic oil before passing the gases thru an ammonia absorber.

5. The method of treating hot coke oven gases whereby creosote oil and carbolic oil are produced directly from the gases, which comprises cooling hot coke oven gases to a regulated temperature and subjecting such gases to a cleaning operation to effect substantially complete separation of pitch constituents therefrom in the form of a pitch having a melting point in excess of 300° F., and subsequently subjecting the cleaned gases to successive condensing treatments at successively lower temperatures to separate therefrom first a creosote oil and then a carbolic oil before passing the gases thru an ammonia absorber.

6. The method of treating hot coke oven gases whereby creosote oil and carbolic oil are produced directly from the gases, which comprises cooling hot coke oven gases to a regulated temperature and subjecting the cooled gases to a cleaning operation to effect substantially complete separation of pitch constituents therefrom in the form of a pitch having a melting point in excess of 400° F., and subsequently subjecting the cleaned gases to successive condensing treatments at successively lower temperatures to separate therefrom first a creosote oil and then a carbolic oil before passing the gases thru an ammonia absorber.

7. The method of treating hot coke oven gases whereby creosote oil and carbolic oil are produced directly from the gases, which comprises subjecting hot coke oven gases to a limited and regulated cooling with ammonia liquor to separate a limited amount of heavy tar therefrom while leaving the gases at a sufficiently high temperature so that upon cleaning the pitch separated will have a high melting point and subjecting the gases at such high temperature to cleaning so as to effect substantially complete removal of pitch particles therefrom without substantial cool-

ing of the gases, and subsequently subjecting the cleaned gases to successive cooling and condensing treatments to separate therefrom first a creosote oil and then subsequently a carbolic oil.

5 In testimony whereof I affix my signature.

STUART PARMELEE MILLER.
